UNITED STATES PATENT OFFICE.

BYRON S. FRYAR, OF SUMNER, WASHINGTON.

REFRIGERATOR-BOX.

No. 827,358.

Specification of Letters Patent.

Patented July 31, 1906.

Application filed February 14, 1905. Serial No. 245,587.

To all whom it may concern:

Be it known that I, BYRON S. FRYAR, a resident of Sumner, in the county of Pierce and State of Washington, have invented certain new and useful Improvements in Refrigerator-Boxes; and I do hereby declare the following to be a full, clear, and exact description of the invention, such as will enable others skilled in the art to which it appertains to make and use the same.

My invention relates to an improved refrigerator-box, the object of the invention being to provide an ice-receptacle extending over the upper end of the box with entrance in one side and box-supports beneath the ice-receptacle which may be removable through an opening in the side of the box beneath the ice-box door and provide a door normally closing the entrance for goods.

With these and other objects in view the invention consists in certain novel features of construction and combinations and arrangements of parts, as will be more fully herein-after described, and pointed out in the claims.

In the accompanying drawings, Figure 1 is a perspective view illustrating my improvements. Fig. 2 is a view in vertical section, and Fig. 3 is a view in section at right angles to Fig. 2. Fig. 4 is an enlarged view in section of the upper portion of the device.

1 represents a box which is shown of rectangular shape, although it may be of other shape, divided by horizontal bars 2, forming an ice-chamber all across the upper end of the box, and the bottom of these bars 2 and bottom 4 of the box have grooves 5 to receive removable frames 6 to support boxes of berries or other goods. One side of the box 1 below partition 2 is open to receive the frames 6 and boxes and is closed by a door 7, hinged at one edge and having suitable securing means, such as shown at 8 and 9, at its other edge.

The ice-chamber contains an ice-pan 3, of galvanized iron or other material, and has a drip-pipe 8' projecting through the wall of box 1 and emptying into a drain-channel 10, protected by a removable casing 11, and the inner end of the drip-pipe 8' is protected by a cap or shield 12, perforated at one end. This cap or shield 12 is made with flanges 13 at both sides to slip beneath guides 14 on the chamber-bottom to hold the cap in position or permit its ready removal.

Entrance to the ice-chamber 3 is permitted through an opening in the box-wall above

door 7, said opening being normally closed by a door 15, hinged at its lower edge and having suitable fastening means 16 at its upper edge. To the inner face of this door 15 a sheet-metal plate 17 is attached by means of a wire 17^a and is snugly held against the upwardly-bent end 18 of the ice-chamber bottom to guide ice therein and prevent any leak at this end of the chamber. The ends 19 of the plate 17 are bent at right angles and are triangular in shape, as shown. These ends 19 have lugs 25 formed by the ends of the wire 17^a, which limit the opening movement of door 17, and said ends 19 also serve to properly guide the ice into the chamber when the door is open.

As the ice-chamber 3 is inclined to sweat, it is necessary to provide means for preventing such moisture coming in contact with the fruit or other goods in the refrigerator. With this end in view the upper faces of the bars 2 are made with longitudinal grooves 20, communicating with grooved uprights 21, and a removable frame 22 is supported on the bars 2. This frame 22 comprises a series of convex boards 24, extending from bar 2 to bar 2 and all connected by bars 23. These convex boards receive the drip of sweat from pan 3 and direct it into the grooves 20, which convey the same into grooved uprights 21 and prevent any contact with the contents of the refrigerator. By making frame 22, bars 2, and uprights 21 entirely of wood there is no sweating of such parts and all formation of moisture thereon is obviated.

By constructing my improvements as above described ice can be readily supplied without disturbing the contents of the refrigerator, and the entire space below the ice-chamber is utilized to receive goods. The device can be easily cleaned and is simple in construction, cheap to manufacture, and strong and durable in use.

A great many slight changes might be made in the general form and arrangement of the parts described without departing from my invention, and hence I would have it understood that I do not restrict myself to the precise details set forth, but consider myself at liberty to make such slight changes and alterations as fairly fall within the spirit and scope of my invention.

Having fully described my invention, what I claim as new, and desire to secure by Letters Patent, is—

1. A refrigerator having an ice-chamber

- provided with a door and an ice-guide attached to the door and free to move over a portion of the floor of the ice-chamber when the door is being closed, said guide adapted 5 to project into the ice-chamber an appreciable distance beyond the doorway when the door is open and guide the ice into the ice-chamber at a point inwardly beyond the doorway.
- 10 2. A portable refrigerator-box having an ice-chamber, a door hinged at its lower edge at one end of said ice-chamber, and an ice-guide pivotally attached at its upper edge to the door at the upper edge of the latter and 15 movable at its free edge on the bottom of the ice-chamber.
3. A portable refrigerator-box having an ice-chamber, a door hinged at one end of said chamber, and an ice-guide hinged at its upper edge to the inner face of the door, said 20 ice-guide comprising a metal plate movable
- on the bottom of the ice-chamber and sides movable parallel with the sides of the ice-chamber.
4. A portable refrigerator-box provided in 25 its upper portion with an ice-chamber having a closed bottom, grooved horizontal bars disposed below the closed bottom of the ice-chamber, uprights having grooves communicating with the grooves of the horizontal bars, 30 and convex pieces over the horizontal bars and below the bottom of the ice-chamber for directing water of condensation into the grooves of the horizontal bars.
- In testimony whereof I have signed this 35 specification in the presence of two subscribing witnesses.
